WILLIAM B. SLAUGHTER, JR., AND RALPH A. GAERTNER, OF LOS ANGELES, CALIFORNIA, ASSIGNORS TO PETER E. SPELLACY, OF LOS ANGELES, CALIFORNIA.

FUEL-NOZZLE FOR SEMI-DIESEL ENGINES.

1,250,684.

Specification of Letters Patent. Patented Dec. 18, 1917.

Application filed October 30, 1916. Serial No. 128,608.

To all whom it may concern:

Be it known that we, WILLIAM B. SLAUGHTER, Jr., and RALPH A. GAERTNER, citizens of the United States, residing at Los Angeles, in the county of Los Angeles and State of California, have invented new and useful Improvements in Fuel-Nozzles for Semi-Diesel Engines, of which the following is a specification.

10. This invention relates to a fuel nozzle and particularly pertains to nozzles adapted to be used to inject liquid fuel into the explosive cylinders of engines of the semi-Diesel type.

One of the difficulties which has been encountered in injecting a liquid fuel into engines of the semi-Diesel type has been that the valve within the fuel nozzle does not always positively discontinue the flow of oil and allows it to continue its flow while the 15 charge within the cylinder is exploding. It is the principal object of this invention to provide a fuel nozzle within which is incorporated a control valve adapted to act automatically and positively to permit and discontinue the flow of liquid fuel to the cylinder.

Another object is to provide a cut-off valve which will act instantly to establish and discontinue the flow of fuel through the nozzle 20 when the fuel pump changes its stroke.

Another object is to provide a combined movable valve member which operates to open and close the fuel valve and also forms an element of the nozzle by which a fine 25 spray of liquid fuel may be obtained.

Another object is to provide a nozzle of a construction which will insure that drops of liquid fuel will not fall into the cylinder after the valve is closed but will be trapped 30 within the nozzle in a manner to prevent dripping.

Another object is to provide a fuel nozzle which is so constructed as to insure the passage of liquid fuel therethrough at a constant velocity throughout its length and thus prevent the retard of its flow from an intended pressure.

It is a further object to provide a fuel nozzle which will thoroughly atomize the 40 liquid fuel passing therethrough and which will be simple in operation and construction.

Another object is to provide a nozzle housing adapted to be screwed through the wall 45 of an engine and having a nozzle and back-

acting valve construction removably mounted upon and in its inner end.

Another object is to provide a nozzle orifice which will deliver an atomizing spray by the pump pressure on the oil. 60

Other objects will appear hereinafter.

The invention is illustrated, by way of example, in the accompanying drawings in which:

Figure 1 is a view in vertical section and elevation as seen taken along the longitudinal center of the nozzle. 65

Fig. 2 is a view in transverse vertical section on the line 2—2 of Fig. 1 and particularly illustrates the manner in which the 70 sectional area of the enlarged bore of the nozzle is maintained equal to the area of the reduced bore.

Fig. 3 is a view in transverse vertical section on the line 3—3 of Fig. 1 and illustrates 75 the series of longitudinal bores extending through the nozzle thimble.

Referring to the drawings more particularly, 10 indicates a fuel supply pipe which delivers a liquid fuel under pressure from a 80 pump to a pipe T 11. The T 11 is fitted at its lower end with a drain-cock 12, its perpendicular fitting 13 being externally threaded to engage the threaded bore 14 formed within the end of the nozzle housing 15. 85

The nozzle housing is substantially cylindrical in shape and extends horizontally from the pipe T. The end adjacent the T is formed in the shape of a hexagon 16 and 90 has a screw threaded neck to permit it to be screwed into a threaded bore within a cylinder wall 17 thus allowing the greater portion of the member to extend into the cylinder. The nozzle housing 15 is formed with a 95 longitudinal bore 18 which extends partly through it and communicates with an aligned bore 19 of enlarged diameter within which the nozzle valve mechanism is mounted. The outer end of the bore 19 is counter-bored, as 100 indicated by the numeral 20, and this counter-bore formed with a conical seat 21. The seat 21 is provided to receive the outer tapered end of a nozzle thimble 22 which is of a diameter and length to fit snugly within 105 the counter-bore 20. The thimble is held in place by a nozzle head 23 which is detachably mounted over the end of the nozzle housing and is formed with oppositely disposed conical bores 24 and 25. The bore 25 110

extends inwardly and represents a cone of small dimensions. The bore 24 extends outwardly and is so arranged that the apices of the two bores meet to form a communicating passage from the interior of the nozzle housing to the engine cylinder. The angularity of the bores 24 and 25 is here shown as substantially equal. It will be understood, however, that this angle may be 10 changed to produce any desired spray of liquid fuel.

The conical bore 24 is adapted to receive a conical filler end 26 of a reciprocating back-acting valve plunger 27. The plunger 15 27 is formed with a frusto-conical back-acting valve shoulder 28 adapted to normally seat upon a valve seat 29 formed in the end of the thimble 22. This seat communicates with a longitudinally extending bore 30 which in turn communicates with a series of 20 fuel passages 31 arranged in a circle concentrically around the line of the bore 30 and through the thimble. These passages are in communication at their inner ends with the 25 enlarged longitudinal bore 19 which in turn communicates with the smaller bore 18. The plunger valve 27 is formed with a shank 32 which extends through a central bore 33 in the thimble and is fitted with a spring seat 30 washer 34 which is held in place by lock-nuts 35. This washer is formed with a series of 35 marginal serrations 36, the combined sectional area of which is approximately equal to that of the bore 18. A coil spring 37 is 40 disposed between the inner end of the thimble 22 and the washer 34 and acts to normally hold the valve shoulder 28 against its seat in the end of the thimble. The opening movement of the valve 28 and the shank 32 is limited by a stop sleeve 38 which fits upon 45 the shank 32 and engages the thimble, so as to adjustably limit the opening of the valve 28 and the seating of the conical point 26.

In operation, liquid fuel is delivered 45 through the supply pipe 10 to the nozzle bore 18 by a reciprocating pump adapted to produce an intermittent pressure within the supply pipe. The reciprocation of the pump is in synchronism with the engine so that 50 fuel will be delivered to the engine at the proper stage of its stroke to insure its compression and most effective combustion. When the fuel within the supply pipe and the nozzle housing 15 is subjected to the 55 pump pressure, the plunger 27 will be moved outwardly and instantly will act to relieve the conical valve shoulder 28 from its seat 29 in the end of the thimble 22. This action will permit fuel to flow through the bore 18 60 into the enlarged bore 19 around the washer 34 by passing through the serrations 36. After the fuel has passed the washer 34, it will enter the thimble through the series of 65 parallel passage-ways 31 and will thereafter be led through the bore in the end of the

thimble to the conical bore 24 formed in the inner face of the nozzle head 23. When the plunger 27 is in its opened position, there will be a small space between the wall of the bore 24 and the conical face of the plunger 70 filler end 26 which will permit the fuel to pass to the bore 25 in a thin film from whence it will be sprayed and thoroughly atomized. The filler end 26 of the plunger fits the bore 24 just close enough to form a 75 thin conical sheet of oil converging outwardly to the orifice. The bevel of the bores 24 and 25 are substantially equal so that the height of the pressure is at the orifice and the lines of flow cross in all directions. 80 When the fuel pressure is discontinued, the coil spring 37 will retract the plunger and draw the conical shoulder 28 against the seat 29, thus discontinuing the flow of fuel in a 85 positive manner.

It will be noted that when the plunger 27 acts to cut off the supply of fuel to the spray orifice of the nozzle, the small particles of the fuel which were not atomized will be trapped within the bore 24 and will drain 90 downwardly and rearwardly therein.

It will thus be seen that the fuel nozzle here described will act effectively to convey a liquid fuel under pressure to an engine cylinder, there atomizing it, and insuring 95 that the fuel will not be injected into the cylinder except in an atomized state.

Especial attention is called to the atomizing spraying orifice formed by the equal angled conical bores 24 and 25 meeting point to point and the mating equal angled conical point 26 vibrating in the inner bore 24. The shape of the spraying orifice is well adapted to thoroughly and finely atomize the oil as it is forced through by the pump pressure, and the conical point 26 assists in this 100 operation and also serves as a needle point to keep the orifice clear and round.

Attention is also called to the fact that the entire back-acting valve mechanism and the orifice may be removed from the housing 15 by unscrewing the cap 23, and that this mechanism is all compactly assembled and mounted in and upon the inner end of the 110 housing, the whole nozzle construction being removable bodily by unscrewing from the engine cylinder.

We claim:

1. In a fuel nozzle, a housing having a central bore adapted to be connected to the source of fuel supply and having a chamber extending from its inner end and connecting to said bore, a thimble mounted in the end of the chamber and having a valve seat from its outer face, a valve for the valve seat, a conical filler end extending outwardly from the valve, an orifice cap secured to the housing and fitting the filler end, a stem for the valve extending through the thimble, a 120 spring around the valve stem against the end 125
2. After the fuel has passed the washer 34, it will enter the thimble through the series of parallel passage-ways 31 and will thereafter be led through the bore in the end of the 130

of the thimble, a spring seat upon the valve stem against the spring, means for limiting the opening of the valve so as not to close the orifice, and means for holding the spring seat in place, there being a passage connecting the bore of the housing through the thimble to the valve seat.

2. In a fuel nozzle, a housing having a central bore adapted to be connected to the source of fuel supply and having a chamber extending from its inner end and connecting to said bore, a thimble mounted in the end of the chamber and having a valve seat from its outer face, a valve for the valve seat, a conical filler end extending outwardly from the valve, a stem for the valve extending through the thimble, a spring around the valve stem against the end of the thimble, a spring seat upon the valve stem against the spring, means for holding the spring seat in place, there being a passage connecting the bore of the housing through the thimble to

the valve seat, and an orifice cap screw-seated upon the end of the housing to cover the thimble and provide an orifice under the control of the valve and having a conical bore to fit the filler end, and there being means to limit the opening of the valve and prevent the filler end from closing the orifice.

3. In a fuel nozzle, a housing, a back-acting valve mechanism mounted in the inner end of the housing, an orifice cap covering the valve mechanism and having an orifice formed by two aligned conical bores meeting point to point, a conical filler end extending from the back-acting valve into the inner conical bore, and means to limit the opening of the back-acting valve so as not to close the orifice.

In testimony whereof we have signed our names to this specification.

WILLIAM B. SLAUGHTER, JR.
RALPH A. GAERTNER.
